UNITED STATES PATENT OFFICE.

HENRY P. LEWANDOWSKI, OF NEW YORK, N. Y.

DESIGN FOR A STATUE.

SPECIFICATION forming part of Design No. 37,160, dated October 11, 1904.

Application filed September 8, 1904. Serial No. 223,781. Term of patent 3½ years.

To all whom it may concern:

Be it known that I, HENRY P. LEWANDOWSKI, a citizen of the United States, residing at New York city, in the county of New York and State of New York, have invented a new, original, and ornamental Design for a Statue, of which the following is a specification, reference being had to the accompanying drawing, forming part thereof.

5 The figure is an elevation of the statue, showing my design.

What I claim as new, and desire to secure by Letters Patent, is—

The ornamental design for a statue as shown.

HENRY P. LEWANDOWSKI.
